(57) **CLAIM**

The ornamental design for the leveling device, as shown and described.

DESCRIPTION

FIG. 1 is a perspective view of a leveling device in accordance with my invention;

FIG. 2 is a front view of the leveling device of FIG. 1;
FIG. 3 is a rear view of the leveling device of FIG. 1;
FIG. 4 is a left side view of the leveling device of FIG. 1;
FIG. 5 is a right side view of the leveling device of FIG. 1;
FIG. 6 is a top view of the leveling device of FIG. 1; and,
FIG. 7 is a bottom view of the leveling device of FIG. 1.
The broken lines of the leveling device in FIGS. 1-7 are
illustrative of portions of the leveling device that form no
part of the claimed design.
